UNITED STATES PATENT OFFICE.

HENRY ROSENBAUM, OF NEW YORK, N. Y.

DESIGN FOR THE ORNAMENTATION OF A SHIRT-FRONT.

SPECIFICATION forming part of Design No. 17,297, dated May 3, 1887.

Application filed March 11, 1887. Serial No. 230,565. Term of patent 3½ years.

To all whom it may concern:

Be it known that I, HENRY ROSENBAUM, of the city, county, and State of New York, have invented a new and Improved Design for a Shirt, of which the following is a full, clear, and exact description.

The leading feature of my design consists in raised transverse figures on the front plait of a shirt, showing two circles united by lines or stripes joining the edges of the two circles.

My design is fully illustrated in the accompanying drawing, to which reference is made.

a a represent two circles or circular ornaments united at their outer edges and in the center to the plait A, and are somewhat raised from the plait, forming slight ovals from the outer edge to the center, and also showing radial lines reaching from the center to the outer edge. The ovals or ornaments a are arranged opposite to each other in pairs, and the ovals of each pair are united by two raised lines or stripes, b, touching the outer edges of both ovals or ornaments a. The lines or stripes b are in the form of lines of beauty crossing each other in the center and their ends touching opposite upper and lower edges of the ornaments or ovals a. At the centers of the lines or stripes b appears a scroll-like figure, c, in the form of the letter S, as illustrated in the drawing, and two stripes, d, lead from the stripes b, meeting the same at about right angles, as shown in the drawing.

I claim—

1. The design herein shown and described for the ornamentation of the front plait of a shirt, the same consisting of two circles, a, oval from the outer edges to the center, and showing radial lines touching the plait at the center and edge of the circles, and the lines or stripes b, reaching from circle to circle.

2. The design herein shown and described for the ornamentation of the front plait of a shirt, the same consisting of two circles, a, the curved stripes b, touching the circles and in the form of lines of beauty and crossing each other between the circles, and the scroll c, shown upon the intersection of the two lines b.
